(57) CLAIM

The ornamental design for a pant, as shown and described.

DESCRIPTION

FIG. 1 is a top plan view of a pant showing my new design; and,

FIG. 2 is a bottom plan view thereof.

The broken lines shown in FIGS. 1 and 2 represent the portion of the design, which forms no part of the claim.

1 Claim, 1 Drawing Sheet
